NATIONAL PNEUMATIC COMPANY, A CORPORATION OF WEST VIRGINIA.

CUSHIONING MECHANISM FOR DOOR-OPERATING DEVICES.

1,001,943.

Specification of Letters Patent. Patented Aug. 29, 1911.

Application filed April 2, 1908. Serial No. 42472.

To all whom it may concern:

Be it known that I, PARIS R. FORMAN, a citizen of the United States, residing at Chicago, county of Cook, State of Illinois, 5 have made a certain new and useful Invention in Cushioning Mechanism for Door-Operating Devices, of which the following is a specification.

The invention relates to cushioning mechanism for pneumatic operating devices.

The object of the invention is to provide means which are simple and efficient for effecting quick starting and slow or cushioned final movements of a door or other 15 closure.

A further object is to provide power mechanism for opening and closing doors and means for efficiently cushioning the final movement of the door without depending upon any throttling operation of a valve.

Other objects of the invention will appear more fully hereinafter.

The invention consists substantially in the construction, combination, location and 25 relative arrangement of parts, all as will be more fully hereinafter set forth, as shown in the accompanying drawings, and finally pointed out in the appended claims.

Referring to the accompanying drawings, 30 and to the various views and reference signs appearing thereon: Figure 1 is a view in elevation, parts broken off, showing a door and power actuated means for moving the door, with means embraced within the scope 35 of my invention for securing a cushioning of the door movement as the door approaches the limit of such movement. Figs. 2 and 3 are enlarged detail views, somewhat diagrammatic, showing a valve construction 40 for controlling the supply and exhaust of operating medium to and from the power mechanism, and suitable for use in accomplishing the objects and purposes of my invention. Fig. 4 is a view similar to Fig. 1. 45 The door and connections thereto from the power mechanism being omitted and showing a modified form of cushioning means embodying the principles of my invention. Fig. 5 is a view in top plan of the construction shown in Fig. 4, and showing diagrammatically an arrangement of valve suitable for use in connection with the modified arrangement of cushioning means. Fig. 6, is 50 a view in side elevation, parts broken out and parts in vertical longitudinal section, showing a power cylinder and the relation

of a control valve with reference thereto. Fig. 7 is a top plan view, somewhat diagrammatic of the same, illustrating the valve operation.

The same part is designated by the same reference sign wherever it occurs throughout the several views.

In the operation of doors and similar closures and other devices, and especially 65 where power operated means are employed to effect the door or closure movements, it is desirable that the movement of the door from its completely open position, in closing, or from its completely closed position, 70 in opening, be initiated quickly, and that, as the door or other device approaches the limit of its movement, whether in opening or closing, it will be cushioned. Where pressure operated means are employed to 75 effect the operation of the door, the cushioning effect is ordinarily accomplished by restricting the exhaust of the operating medium from the power cylinder as the door 80 approaches the end of its movement. This 85 has heretofore been accomplished by automatically or otherwise reducing the area of the passage through which the exhaust of the pressure medium is effected, at some convenient point, as the door nears the end 90 of its movement, and one common form of means employed for this purpose has been a valve, by the operation of which the area of exhaust opening may be varied by closing or opening, more or less, the size of the exhaust ports.

In accordance with the principles of my invention I propose to accomplish the desired objects without depending upon or using the valve to vary or control the size 95 or area of the exhaust ports, and in carrying out my invention I employ a tank reservoir or receptacle which for brevity, and also to indicate breadth and scope I will hereinafter refer to as an expansion chamber, 100 into which the operating medium, after having accomplished its work in the power cylinder, is permitted to flow when the exhaust port from the power cylinder is opened, whereby the exhaust pressure is 105 reduced by expanding into the expansion chamber. I provide the expansion chamber with a restricted opening to the atmosphere, whereby the expanded exhaust pressure medium may gradually escape. In this 110 manner I avoid entirely the necessity of relying on a valve to vary or control the

area of an exhaust port in order to secure the desired cushioning effect as the door nears the end of its movement.

Referring to the accompanying drawings, 5 reference sign A, designates a door or other closure to be moved; B a rocking lever having connection with the door to move the same; D, a power cylinder to which an operating medium, such as compressed air, is 10 supplied to operate a piston P, see Fig. 6, within said cylinder; C, is the piston rod which is connected to the door operating lever B for rocking the same. To operate the piston and rod C, an operating medium, 15 in this instance compressed air, is admitted to and exhausted from the respective ends of the cylinder. The supply and exhaust of the operating medium to and from the cylinder D, is controlled by a valve F, see 20 Figs. 2 and 3, operating in a casing E, see Fig. 1. The valve F, which is placed in the casing E, operates over a seat plate G, through which are formed the port openings 6, 7, 8 and 9, the valve F, controlling 25 said openings. The pressure medium is supplied to the casing E through port 6. The ports 8 and 9 respectively communicate 30 through pipes 30, 31 with opposite ends of the cylinder D, and the port 7, is for the exhaust from the cylinder. The pressure supply pipe 10, communicates with a convenient source of pressure supply and delivers into casing E, through the port 6. The exhaust pipe 11, is in communication 35 with the exhaust port 7. The valve F is provided with a recess 12, on the face thereof, of which bears against the seat plate G, as indicated in dotted lines in Figs. 2 and 3, and which recess is arranged and designed 40 to establish communication between exhaust port 7, and one or the other cylinder ports 8 or 9, as the case may be, according to the angular position into which the valve F, may be moved. As shown in Fig. 2, the 45 valve F occupies a position to uncover port 8 to the supply port 6, and to bring ports 7 and 9 into communication with each other, whereby the pressure medium is admitted to one end of the cylinder D, from supply 50 pipe 10, through port 6, into casing E, and thence through port 8, while at the same time the other end of the cylinder is opened to exhaust through port 9, the recess 12, exhaust port 7, and pipe 11. In Fig. 3, the 55 valve F, is shown in position to uncover ports 9 and 6, and to bring ports 7 and 8 into communication with each other, thereby admitting the pressure medium through supply pipe 10 into chamber E, through port 6, 60 and thence through port 9 to that end of the cylinder with which the said port 9 communicates, while at the same time the opposite end of the cylinder is opened to exhaust through port 8, recess 12, port 7 65 and exhaust pipe 11. The valve F, may be

shifted to effect the above described operation in any suitable manner. I have shown the stem of the valve extending through the casing E, and to which stem an operating rod may be attached, see Fig. 1.

The parts so far described may be of the usual or any well known construction and arrangement and in the specific details thereof are not of my invention.

As above explained, when the valve F is moved into the position shown in Fig. 2 or that shown in Fig. 3, then one end of the cylinder is freely open to the pressure supply, while the other end of the cylinder is open to exhaust. Under these conditions the door or other device to be moved will begin its movement rapidly, which movement would continue to the full end of the travel of the door, thereby causing an objectionable slam and jar when the door reaches the end of its travel, unless some means are provided for cushioning the final movement thereof. In order to avoid this slam and jar, and to provide means for cushioning the final movement of the door and without employing the valve to effect, a partial closing or throttling of the area of the exhaust port, I propose, in accordance with the principles of my invention, and as above indicated, to provide a chamber into which the exhaust pressure from the exhausting end of the cylinder may expand, but from which chamber the pressure may escape slowly to the outer air. This may be accomplished in many different ways, as, for instance, by permitting the exhaust air to expand into a pipe, tank, reservoir, or the like, indicated at 4, to which the exhaust pipe 11, delivers, and which expansion chamber 4, is provided with a small opening 14, to the atmosphere. With this arrangement it will be readily seen, that when the valve F, is shifted into position to admit the pressure medium to one end of the cylinder, the other end of the cylinder is opened to the expansion chamber and thence, through the restricted opening 14, to the atmosphere. The exhaust air from the exhausting end of the cylinder is thus permitted to expand into the larger area afforded by the expansion chamber, thereby so reducing the pressure thereof as to enable the supply pressure in the other end of the cylinder to initiate a quick movement of the door. As the door continues its movement, however, the travel of the piston in the cylinder reduces the space occupied by the exhaust air, and since the final escape of the exhaust air is retarded by having to pass through the restricted area of the opening 14, in chamber 4, the pressure which is imposed upon the exhaust air contained in the expansion chamber 4, the pipe 11, and the exhausting end of the cylinder D, increases by the movement of the piston to 120 125 130 135 140 145 150 155 160 165 170 175 180 185 190 195 200

ward the exhausting end of the cylinder thereby producing the desired cushioning effect as the door approaches the limit of its travel, the continued escape of the exhaust air from the expansion chamber through the small opening 14, enabling the piston of the power cylinder to complete its stroke, but at a reduced rate of speed. It is obvious that the faster the power cylinder piston, and hence, also, the door, may try to move, under the influence of the live pressure supplied to the operating end of the cylinder, the greater will be the compression of the exhaust air in the expansion chamber, and hence, the greater will be the resistance to the movement of the piston and door.

By the arrangement above described I am enabled to secure a quick starting movement of the door, and a gradually increasing cushioned effect, and without the use of any moving valve or other device to secure a choking or throttling of the path of the exhaust pressure.

It may sometimes be desirable to quickly reverse the movement of the door before the exhaust air has had sufficient time to escape from the expansion chamber and the exhaust pipe 11, and the exhausting end of the power cylinder D, and hence when the reverse movement of the door commences the expansion chamber 4, and pipe connection 11, are already full of air under a greater or less degree of compression, and therefore in place of a free and quick starting movement of the door, the door would have a slow sluggish movement at the start which will continue in this condition throughout the extent of such movement. In order to obviate this, a separate expansion chamber may be provided for each end of the power cylinder, and a separate exhaust pipe leading to each expansion chamber. Such an arrangement is shown in Figs. 4 and 5. In this case the valve 15, is provided with two recesses or ducts 16, 17, in its bearing face, and separated from each other by the intermediate wall 18. The valve cooperates with a seat 19, in which are provided the pressure supply port 20, the ports 21, 22, respectively communicating with opposite ends of the power cylinder D, and also two exhaust ports 23, 24, respectively communicating with the expansion chambers 25, 26, each of said chambers having a restricted opening to the atmosphere, as indicated at 27, and similar to the opening 14, in expansion chamber 4, above described with reference to the arrangement shown in Fig. 1, and having a similar function. The recess 16, in the valve 19, is of sufficient length to bring the cylinder port 21 into communication with exhaust port 23, and similarly, the recess 17, in the valve

is of sufficient length to bring the cylinder port 22, and the exhaust port 24 into communication with each other, when the valve is suitably actuated. Thus it will be seen that instead of the exhaust from both ends of the cylinder being made through a common connection and into an expansion chamber common to both, a separate exhaust connection, and a separate expansion chamber is provided for each end of the cylinder. With this arrangement it will be readily seen that while the door is moving in one direction there will be ample time for a complete exhaust of the air from that end of the cylinder where the cushioning effect is secured should the movement of the door be reversed, and hence I am enabled to secure a quick starting and a slow or cushioned final movement of the door whether the movement of the door be quickly reversed or not.

Having now set forth the object and nature of my invention, and constructions embodying the principles thereof, what I claim as new and useful and of my own invention, and desire to secure by Letters Patent is:

1. In a cushioning mechanism for door operating devices, a power cylinder, a piston operating therein, door moving devices operated by the piston supply and exhaust ports for the power cylinder, and a valve for controlling said ports, in combination with an expansion chamber communicating with an exhaust port, and having an opening of restricted area to the atmosphere.

2. In an apparatus of the class described, a power cylinder, supply and exhaust ports therefor, and a valve for opening and closing said ports, and means into which the exhaust from one end of the cylinder is permitted to expand, when pressure is supplied to the other end of said cylinder, said means having a restricted path to the atmosphere, whereby the movement inaugurated by the power cylinder is initially rapid, and finally cushioned.

3. In an apparatus of the class described, a power cylinder, supply and exhaust ports for each end thereof, and a valve for controlling said ports, in combination with an expansion chamber associated with each exhaust port and having a restricted opening to the atmosphere.

In testimony whereof I have hereunto set my hand in the presence of the subscribing witnesses, on this twenty-fourth day of March A. D., 1908.

PARIS R. FORMAN.
